UNITED STATES PATENT OFFICE.

ALVAH B. CLARK, OF SPRINGFIELD, MASSACHUSETTS.

DESIGN FOR AN ICE-SHAVER.

SPECIFICATION forming part of Design No. 28,988, dated July 5, 1898.

Application filed January 10, 1898. Serial No. 666,252. Term of patent 7 years.

To all whom it may concern:

Be it known that I, ALVAH B. CLARK, a citizen of the United States, residing at Springfield, in the county of Hampden and State of Massachusetts, have invented and produced a new and useful Design for Ice-Shavers, of which the following is a specification, reference being had to the accompanying drawings, and characters of reference marked thereon forming a part of this specification, and of which—

Figure 1 shows a bottom perspective view of my novel design. Fig. 2 is a central vertical longitudinal section of the same. Fig. 3 shows a plan view. Figs. 4 and 5 are cross-sections on lines B B and C C, respectively.

As shown in the drawings, the leading or material feature of my design consists in an open bowl, the bottom of which is slightly

contracted, having straight sides 2 2, a rounded inner end wall 3, and a straight outer end 4, the latter being extended below the base and forms a cutting edge 5 adjacent to the opening 6 of the bottom. Integral with the rounded end 3 is formed a handle, comprising an oval or convex top surface 7, containing a central orifice 8, and the concave bottom 9; said handle being broadest adjacent to its free end.

Having thus described my invention, what I claim as new, and desire to secure by Letters Patent, is—

The design for an ice-shaver as herein shown and described.

ALVAH B. CLARK.
